UNITED STATES PATENT OFFICE.

PAUL GUILMAN, OF EAST ST. LOUIS, ILLINOIS.

MINER'S LAMP.

1,090,051.

Specification of Letters Patent.

Patented Mar. 10, 1914.

Application filed October 28, 1913. Serial No. 797,817.

To all whom it may concern:

Be it known that I, PAUL GUILMAN, a citizen of the United States, residing at East St. Louis, in the county of St. Clair, State of Illinois, have invented certain new and useful Improvements in Miners' Lamps; and I do hereby declare the following to be a full, clear, and exact description of the invention, such as will enable others skilled in the art to which it appertains to make and use the same.

This invention relates to miners' lamps and has for an object to provide means for positively preventing displacement of the water regulating valve so that the effective operation of the lamp will be at all times assured.

It is well known that in acetylene miners' lamps the water regulating valve when displaced will either let too much water flow into the carbide chamber or else will shut off the water altogether, which in either case results in the lamp becoming extinguished. To obviate this difficulty I provide a novel means for mounting the valve stem so that it is positively housed against accidental displacement, and may be gotten at easily for adjustment by simply removing the filling cap of the water receptacle.

With the above objects in view the invention consists of certain novel details of construction and combination of parts herein-after fully described and claimed, it being understood that various modifications may be made in the minor details of construction within the scope of the appended claim.

In the accompanying drawing illustrating this invention:—Figure 1 is a longitudinal sectional view through a miner's acetylene lamp embodying my improvements. Fig. 2 is an enlarged sectional view on the line 2—2 Fig. 1. Fig. 3 is an enlarged fragmentary sectional view showing the valve stem securing means with the cap in place. Fig. 4 is a plan view of the parts shown in Fig. 3 with the cap removed.

Referring now to the drawing in which like characters of reference designate similar parts, the miner's lamp, is shown to comprise a carbide receiving generating chamber 10 that carries on its top a removable water tank 11 that is closed by a concaved top 12, there being an attaching hook 13 on one side of the tank and a lamp reflector 14 and burner 15 on the opposite side of the lamp,

the burner being connected by a tube 16 to the generating chamber. A water pipe 17 opens through the bottom of the tank and enters the generating chamber where it is provided with outlet orifices 18 from which the water escapes and combines with the carbide to generate the acetylene gas. These parts are all of the usual kind.

In carrying out my invention the concave top 12 of the tank is provided with a central filling opening 19. Projecting up through this opening and of smaller diameter than the opening is a cylindrical externally threaded tube 20 that is secured stationary to the tank wall by means of a spider 21. A nut 22 is fixedly secured to the spider below the tube by means of a band 23. The valve stem 24 seats at the lower end in the intake end of the water outlet pipe 17 and is formed at the upper end with screw threads 25 which engage in the screw threads of the nut. The valve stem projects up through the tube and is equipped with a butterfly or wing head 26 by means of which the valve may be advanced or retracted through the nut to control the flow of water through the outlet pipe. A cap 27 is provided with internal screw threads 28 that engage with external screw threads 29 on the tube 20, the cap also being provided with a base flange 30 that bears upon the marginal edges of the filling opening in the top of the tank. It is now evident that the cap 27 positively houses the valve against displacement from contact with external objects, while by simply removing the cap the valve may be adjusted easily and quickly.

The tank may be filled by pouring the water down through the tube 20 from whence it escapes through the spider 21, whatever water spilled on the concaved top of the tank gravitating into the tank through that portion of the filling opening 19 that surrounds the tube 20. By virtue of this construction it will be seen that the water supply in the tank may be replenished from time to time without disturbing the position of the valve, and that further the valve may be removed for cleaning at any time without disturbing the position of its mountings.

What is claimed, is:—

In an acetylene lamp, a tank, there being a filling opening in the tank top, a threaded tube projecting through and of smaller di-

ameter than said opening, a skeleton member securing said tube to the inner wall of said tank, a nut carried by said member below and in alinement with said tube, a valve having a threaded stem engaged through said nut and passing through said tube, and a cap threaded on to said tube and having a base flange engaging the marginal edges of said opening, said cap housing said stem

against displacement and closing said filling opening.

In testimony whereof, I affix my signature, in the presence of two witnesses.

PAUL GUILMAN.
